UNITED STATES PATENT OFFICE.

MAURICE H. COHEN, OF PHILADELPHIA, PENNSYLVANIA.

LABEL-HOLDING CAP OR COVER OF A CAN, JAR, OR OTHER BODY.

1,215,114.

Specification of Letters Patent.

Patented Feb. 6, 1917.

Application filed June 29, 1916. Serial No. 106,560.

To all whom it may concern:

Be it known that I, MAURICE H. COHEN, a citizen of the United States, residing in the city and county of Philadelphia, State 5 of Pennsylvania, have invented a new and useful Label-Holding Cap or Cover of a Can, Jar, or other Body, of which the following is a specification.

My invention consists of a cap or cover of 10 a can, jar, etc., constructed of suitable material such as metal, to hold a label thereon in a simple and inexpensive manner so that it will retain its position without liability to crimp or shift.

15 It consists also of the formation of the inner upper edge of the device, whereby the hand will not be cut by the same, and the label is not liable to be abraded or cut through.

20 The invention is satisfactorily illustrated in the accompanying drawing, but the important instrumentalities thereof may be varied, and so it is to be understood that the invention is not limited to the specific 25 details shown and described.

Figure 1 represents a perspective view of a label holding cap or cover embodying my invention.

Fig. 2 represents a vertical section of the 30 same in perspective, including also the body of the can, jar, etc.

Similar numerals of reference indicate corresponding parts in the figures.

Referring to the drawings.

35 1 designates the cap or cover of a can, jar, etc., the same being formed of integral members comprising the side wall 2, the outwardly channeled rim 3 at the upper end of said side wall, the flange 4 which is extended inwardly from the upper terminal 40 of said rim, the rounded edge 5 of said flange, the downwardly-extending bead 6 at or about the junction of the rim 3 and the flange 4, and the upwardly-extending bead 45 7 at or about the junction of the rim 3 and the upper end of the side wall 2 of the top.

The upper end of the cap or cover is closed by the disk 8 of metal or other suitable material, its peripheral portion entering the channel of the rim 3 and being seated on the top of the side wall 2. On said disk is a label 9 of paper, card-board or other desired material, its peripheral portion entering the channel of the rim 3 and

being engaged by the inner face of the flange 55 4, leaving the main portion of the label exposed to view.

Attention is directed to the fact that the beads 6 and 7 are produced by swaging the inner terminals of the wall of the rim 3, 60 said beads engaging the contiguous peripheral portions of the disk 8 and label 9 and pressing and clamping them together, thus holding the label and disk as one, preventing shifting or movement of the same, more particularly of the label, while the disk provides a reliable closure of the top of the cap or cover.

The inner terminal of the flange is turned or doubled on itself forming the rounded 70 edge 5 as heretofore referred to, the same placing the raw edge of said terminal under the main portion of said flange, whereby the hand will not contact with and be cut by the same, nor will the label be abraded and cut 75 by said raw edge, as said rounded edge 5 presents a smooth bend on said inner terminal of the flange.

Having thus described my invention what I claim as new and desire to secure by Letters Patent, is:—

1. A cap or cover of a can, jar, or like body, composed of integral members comprising a side wall, an outwardly channeled rim on the upper end of said side wall, a 85 flange inturned from the inner terminal of said rim, said flange leaving a central opening in the cap, the opposite terminal walls of said rim being disposed to clamp opposite sides of a label with its central portion appearing at said opening.

2. A cap or cover of a can, jar, or like body, composed of integral members comprising a side wall, an outwardly channeled rim on the upper end of said side wall, a 95 flange inturned from the inner terminal of said rim, said flange leaving a central opening in said cap and oppositely extended beads at the junctions of said rim, side, and flange respectively.

3. A cap or cover of a can, jar, or like body, composed of integral members comprising a side wall, an outwardly channeled rim on the upper end of said side wall, a flange inturned from the inner terminal of said rim, a disk-like member seated on the top of said side wall, and a label imposed on said member, the peripheral portions of

100

105

said label and member being adapted to enter said channeled rim, and opposed means at or about the inner terminals of the wall of said rim adapted to clamp directly between them said member and label about the peripheral portions thereof, said member resting upon the lowermost of said means.

4. A cap or cover of a can, jar, or like body, composed of integral members comprising a side wall, an outwardly channeled rim on the upper end of said side wall, and a flange inturned from the inner terminal of said rim, said flange leaving a central opening in said cap, the terminal portion of said flange being doubled on itself forming a rounded edge of said portion, said cap

being formed with oppositely extended beads at the inner sides of said rim.

5. A cap or cover of a can, jar, or like body, comprising in a single integral element a depending side wall, an outwardly channeled rim on the upper end of said side wall and a flange inturned from the inner terminal of said rim and leaving a central opening in said cap, said rim being formed with oppositely disposed beads at its junction with said side wall and flange to support and clamp a label therebetween. 25
